UNITED STATES PATENT OFFICE.

MICHAEL A. DROITCOUR, OF DELPHOS, OHIO.

GRIPPER-MOTION.

1,275,002.

Specification of Letters Patent.

Patented Aug. 6, 1918.

Application filed December 24, 1917. Serial No. 208,639.

To all whom it may concern:

Be it known that I, MICHAEL A. DROITCOUR, a citizen of the United States, residing at Delphos, in the county of Van Wert 5 and State of Ohio, have invented certain new and useful Improvements in Gripper-Motions; and I hereby declare that the following is a full, clear, and exact description thereof, reference being had to the accompanying drawings, which form part of this specification.

This invention is an improvement in gripper mechanisms such as are used on the impression cylinders and transfer reels of printing presses and in other mechanisms wherein cylinders or reels provided with grippers are used to handle sheets of paper and the like, or to transfer such sheets from one point to another.

20 The object of the present invention is to simplify and improve the means for operating the grippers; to cause the grippers to securely hold the sheets when closed thereon; to remain in inoperative position when 25 opened; to lessen the shock and strain upon the tumbler and tumbler-pins in opening and closing the grippers; and to provide an efficient gripper mechanism which will be capable of operating easily and reliably at 30 high speeds.

I will explain one preferred embodiment of the invention as illustrated in the accompanying drawings and summarize in the claims the essential features and combinations 35 of parts for which protection is desired.

In said drawings:

Figure 1 is a partial end elevation of a cylinder provided with my novel gripper 40 operating mechanism and showing the grippers closed in full lines.

Fig. 2 is a top plan view of Fig. 1 showing the gripper actuating devices.

Fig. 3 is a view similar to Fig. 1 but 45 showing the grippers opened.

The cylinder 1 may be the impression cylinder of a printing press, or a transfer cylinder or reel for handling sheets. A rock shaft 2 carrying the gripper fingers is 50 mounted in said cylinder in the usual manner, and has a slotted tumbler 2^a on its outer end, which in the construction indicated is adapted to be alternately engaged by tumbler-pins 3 and 3^b, which may be mounted 55 adjacent the end of the cylinder and operated in the usual manner by suitable means, not shown, so that each will be pro-

jected at the proper time into position to engage the tumbler and operate the same in the usual manner and then retracted out of 60 the way.

Attached to the gripper shaft 2 are gripper fingers 2^b which are adapted to engage the end of the sheet when the grippers are closed (as in Fig. 1) and to release the 65 sheet when the grippers are opened, as in Fig. 3.

Mounted on the shaft 2 adjacent the tumbler 2^a is a cam disk 4 which is preferably substantially circular, and is provided with a major peripheral recess 4^a which is engaged by the controlling device when the grippers are closed (see Fig. 1); and with a minor peripheral recess 4^b which is also engaged by the controlling device when the 75 grippers are opened (see Fig. 3).

These recesses 4^a and 4^b are adapted to be engaged by the controlling device, which is preferably a roller 5 mounted on a pin 5^a, supported in the bifurcated head 6^a of a 70 rod 6, which rod passes through an eye 6^b attached to the cylinder head. An expansion spring 6^c is preferably strung on the rod between the head 6^a and the lug 6^b so as to normally project the roller toward the 75 cam. The movement of the roller toward the axis of the cam however is controlled by the link 7 shown as having a bifurcated end 7^a embracing the head 6^a and pivotally connected with the pin 5^a; and the other end of 80 the link 7 is pivoted on a stud 7^b attached to the cylinder head within the gripper pocket in the cylinder.

The link 7 controls and limits the inward movement of the cam roller 5 toward the 95 shaft 2, and the spring 6^c normally tends to project this roller past cam 4; and it will be observed that when the roller 5 is engaged with the recess 4^a the line of movement of the cam roller 5 under the action of the 100 spring 6 is practically perpendicular to a radial line drawn from the axis of the shaft 2 or cam 4 as indicated by the dotted lines X—X in Fig. 1. Consequently the spring pressure is not directed inward toward the 105 axis of the cam 4 but against one end of the recess 4^a; and when roller 5 is in recess 4^a practically the full pressure of the spring is exerted on cam 4 to directly close the fingers 2^b and hold them forcibly but yieldingly in contact with the edge of the pocket, so that they will yieldingly but securely 110 grip the edge of a sheet of paper S, which has been placed in position to be engaged by

the grippers, when they close in the well understood manner.

At the time in the revolution of the cylinder when it is desired to open the grippers 5 the pin 3^b is moved into position to engage tumbler 2^a, see Fig. 3, said pin 3^b being so located as to enter the mouth of the slot in the tumbler and as the cylinder rotates cause the tumbler to turn the gripper shaft 10 2 approximately 120 degrees to the position indicated in Fig. 3; in which position the cam roller 5 engages the minor notch 4^b in cam 4 and will hold the grippers securely open.

15 The recess 4^b in cam 4 is preferably smaller and more shallow than recess 4^a, and when the roller 5 engages recess 4^b, see Fig. 3, the point of contact of the roller against the cam member 4 is almost directly below the cam shaft 2 and the link 7 then controls 20 the movement of the roller so that the spring has little or no tendency to rotate the gripper cam, as it does when the parts are in the position shown in Fig. 1, but the 25 roller will hold the cam 4 and retain the grippers in open position.

A stop 8 may be provided to prevent excessive movement of the grippers 2^b in either direction.

30 When the tumbler first engages the pin the initial movement of the tumbler moves the roller back as indicated in dotted lines in Fig. 1 against the tension of the spring 6^c until the cam roller rides upon the circular portion 4^c of the periphery of the cam 4, whereupon the pressure of the spring on or against the cam is practically neutralized and the cam roller then has an easy uniform 35 rolling contact with the cylindric portion 4^c of the cam 4; therefore, except on the initial starting movement of the cam there is only a rolling pressure between the cam roller and the cam, which makes it very 40 easy for the tumbler and pin to shift the gripper shaft and takes strain off of the tumbler pin and tumbler. In turning the gripper shaft practically the only duty performed by the pin and the tumbler after the cam roller disengages the recess in the 45 cam, is that of continuing the turning movement of the shaft 2 until the cam roller engages the other recess in the cam.

With this invention the usual auxiliary crank arm on the gripper shaft and double 55 motion spring connections engaging said arm to hold the grippers in open or closed position, are dispensed with; the only opposition to movement of the tumbler offered by the spring is that which is required to 60 disengage the roller 5 from the recess (4^a or 4^b) with which it may be in engagement at the moment of starting the tumbler. When the tumbler is engaged by a pin in

starting to swing the grippers open or closed the tumbler has a long leverage which enables it to easily overcome the spring, and renders its action easy and gentle, and permits of high speed. The ease of movement is due to the peculiar mounting of the cam roller; and when the roller is engaged with recess 4^a the pressure of the spring is exerted in the first instance to directly and positively hold the fingers closed, and the fingers can readily and securely hold sheets of different thickness. 75

What I claim is:

1. A gripper mechanism comprising a gripper carrying shaft and devices for rocking same; a cam-member on said shaft having a parti-circular portion and recesses at 80 separated points of said portion, a controlling member adapted to engage said recesses when the shaft is rocked, spring actuated means carrying said member, and means to limit the movement of said member toward the rock shaft whereby when the grippers are closed the action of the spring is effectively directed against the cam member substantially at right angles 85 to a radial line emanating from the gripper shaft. 90

2. In combination a cylinder, a rock shaft therein carrying grippers, a tumbler on the end of said shaft, and devices engaging said tumbler to shift the same; with a cam on 95 said shaft having spaced recesses in its periphery, a cam roller beside said cam adapted to yieldably engage the periphery of the cam and to enter the recesses therein; a movable spring projected member to 100 which the cam roller is connected, and a link pivotally connected with said member and to an adjacent pivot on the cylinder; all so arranged that when the grippers are closed the spring forces the cam to positively but yieldingly hold the grippers in 105 closed position.

3. In combination, a gripper carrying shaft, a tumbler thereon, and tumbler engaging devices; with a cam on said shaft 110 having a parti-circular portion and spaced recesses in its periphery, a cam roller adapted to engage said cam and to enter the recesses therein; a spring-projected rod carrying said cam roller, and a link pivotally connected with said cam roller and with a fixed point adjacent the cam to limit the inward movement of said cam roller; whereby when the grippers are closed the pressure of the spring is effectively directed 115 against the cam at substantially right angles to a radial line projected from the axis of the gripper shaft. 120

In testimony that I claim the foregoing as my own, I affix my signature.

MICHAEL A. DROITCOUR.
